COMPRESSION TESTER FOR DETERMINATION OF FASTNESS TO PERSPIRATION OF DYED TEXTILES

Henry E. Millson, Plainfield, Herbert L. Parsons, Highland Park, and Matthew J. Babey, Raritan, N. J., assignors to American Cyanamid Company, New York, N. Y., a corporation of Maine

Application February 8, 1949, Serial No. 75,142

3 Claims. (Cl. 73—159)

1

This invention relates to an improved device for carrying out perspiration tests on dyed fabrics and more particularly an apparatus permitting accurately reproducible results.

In the past, tests for determining color fastness to perspiration have been carried out by wetting out the test specimen, in combination with an undyed piece of fabric, which is usually a piece of multifiber fabric, in a standard solution recommended for the purpose by the American Association of Textile Chemists and Colorists (Yearbooks 1947-1948, pp. 114-115). After the excess of standard perspiration solution is expressed from the test specimen, it is rolled together with a piece of undyed fabric in such a manner as to keep the test specimen on the inside. The rolled fabrics are then inserted into a glass tube, which is closed at one end, in such a manner that about one-third of the roll extends from the open end of the tube. The tube containing the rolled fabrics is then placed in an oven, usually set at 100° F. for the requisite time for the test. It has long been recognized that this method is inadequate particularly where bleeding of the dye is encountered and that three factors had great influence on the results obtained, namely, time, temperature and uniformity of contact between the test specimen and the undyed fabric. Uniform contact between the two fabrics can be maintained only if there is uniform pressure exerted on the two fabrics. By the very nature of the operation it has been practically impossible to keep the pressure and contact constant. The pressure exerted upon the two fabrics is dependent first of all upon how tightly the fabrics are rolled together and secondly upon whether the uniformity of this roll is maintained for the duration of the test. This non-uniformity of pressure on contact between the two fabrics led to inconsistent results between two tests in addition to extreme variations in individual tests as well as variation in results with the same sample.

The present invention avoids the difficulties encountered in the previously used method and apparatus and permits carrying out a large number of tests under accurately calibrated conditions in which the pressure may be quite high and these tests may be reproduced exactly time after time. Essentially the device of the present invention compresses the test samples, which are separated by impervious plates, between two blocks, the pressure being measured on a spring balance. The device is mounted on a frame sufficiently small to be readily introduced into a drying oven. The pressure can be exactly repro-

duced in other samples by compressing the plates until the spring balance reads the same pressure and thus with the device of the present invention the tests are in no way influenced by human variables in the tightness of the rolls of the test samples which has been one of the drawbacks encountered in the method heretofore used.

It is an additional advantage of the present invention that the time of preparing samples is greatly reduced. It is no longer necessary to roll carefully each sample to attempt to obtain uniform pressure and to put each in an individual glass tube. On the contrary, a number of samples can be stacked with spacer plates between the compressing plates of the device of the present invention and as many as thirty samples may be tested at the same time resulting in a greatly reduced amount of labor required.

It is a further advantage of the apparatus of the present invention that it is made of very rugged components and that the cost is moderate as no complicated mechanism is required. This facilitates the use of a precision tester in laboratories where the number of tests made is not great and no excessive investment is required which restricts the field of utility of accurate perspiration testers.

The invention will be described in greater detail in conjunction with the drawings, in which:

Fig. 1 is a side view of the apparatus;
Fig. 2 is a plan view;
Fig. 3 is a detailed vertical section of the sample holder portion of the apparatus taken on the line 3—3 of Fig. 2;
Fig. 4 is a view partly in section along the line 4—4 of Figs. 1 and 2, and

Fig. 5 is an exploded view of the parts of the test sample holder.

Reference numeral 1 indicates a suitable base or frame. Fixedly secured at the forward end thereof is fixed plate 12 which carries upper and lower guide rods 2. Compression blocks 3 which may be of any material that is not corroded by the solution are mounted so as to ride on lower guide rods 2, the upper guide rods 2 serving to hold blocks 3 in an upright position. Movable plate 4 is mounted on upper and lower guide rods 2. Plate 4 is movable longitudinally of frame 1 by means of screw 6, threaded through a suitable aperture in plate 12 and secured to plate 4. Plate 12 is provided with a set screw 11 for locking set screw 6 in position. Movable plate 5 is positioned so as to ride on lower guide rods 2. Rod 7 is secured to plate 5 by means of a suitable annular flange 16. Coupling 8 secures rod 7 to rod 9.

which in turn actuates spring balance 10 mounted on base portion 1a which is detachably secured to base 1 as shown. Clamping screw 15 mounted upon a suitable standard 17 is adapted to lock rod 7 in position as shown in Figure 4. Test specimens 13 and spacer plates 14 may be mounted between compression blocks 3 as shown in Figure 3.

The operation of the invention will be described in conjunction with the particular examples illustrated in Figure 3. A number of test specimens are wet with the standard perspiration testing solution and are stacked between the stainless steel or glass plates 14 in the sample holder. Assuming that it is desired to carry out the test under a pressure of seven and a half pounds, the screw 6 is turned down until the spring balance shows seven and a half pounds pressure as is illustrated in Figure 2. Then the screw is locked by the locking set screw 11 and the whole assembly is placed into a suitable drying oven maintained at the desired temperature for the test.

After the test is completed, the screw 11 is released, the screw 6 backed off and the test specimens removed. The test is accurately reproducible because the same pressure can be obtained in a subsequent test.

When a very large number of test samples are to be tested at the same time it is possible to remove the blocks 3 and fill up the sample holder between the plates 4 and 5 with test specimens and stainless steel spacer plates. In this manner it is possible to test as many as thirty samples at one time. However, it is more often desirable to test a smaller number of samples and therefore the device of the present invention will be more commonly used with the spacing blocks 3 in place permitting accurate testing of a smaller number of samples.

It will be noted that the base is preferably composed of two sections connected by a dove-tailed mortice and tenon joint as is shown in Figure 1. Rods 7 and 9 can also be uncoupled from each other by loosening the coupling 8. It is thus possible to prepare a number of sets of test specimens for use with the same balance. In such a case, the correct tension is applied by means of screw 6, the rod 7 is locked by the clamping screw 15 and the whole upper portion of the device removed and a new assembly substituted. This has the advantage of requiring only a single spring balance and the space taken in a testing oven is considerably smaller than when the whole device is placed therein.

We claim:

1. In a perspiration fastness tester, the combination comprising a support, a vertically disposed end plate secured to said support, a plurality of

5 laterally spaced guide rods extending substantially horizontally outwardly from said plate, a movable plate mounted on said rods, a second movable plate adapted to ride on said rods and disposed in substantially horizontal alignment with respect to said first-mentioned movable plate, screw means secured to said first-mentioned movable plate and adapted to move said plate longitudinally of said rods and of said support, 10 and a force measuring means secured to said second-mentioned movable plate and to said support.

15 2. In a perspiration fastness tester, the combination comprising a support, a vertically disposed end plate secured to said support, a plurality of laterally spaced guide rods extending substantially horizontally outwardly from said plate, a movable plate mounted on said rods, a second movable plate adapted to ride on said rods and disposed in substantially horizontal alignment with respect to said first-mentioned movable plate, a plurality of compression blocks mounted 20 between said movable plates, a plurality of spacer plates mounted between said compression blocks, screw means secured to said first-mentioned movable plate and adapted to move said plate longitudinally of said rods and of said support, and a force measuring means secured to said second-mentioned movable plate and to said support.

3. A device as in claim 2, wherein said support is composed of two detachably secured segments, wherein said force measuring means is mounted upon one of said segments and said plates are mounted upon the other of said segments, and 30 wherein a second screw means is provided for locking said second-mentioned movable plate in a fixed position.
